DESIGN FOR A FISHING ROD HANDLE OR ANALOGOUS ARTICLE

Louis Gurrieri, New York, N. Y.

Application October 4, 1938, Serial No. 80,237

Term of patent 3½ years

To all whom it may concern:

Be it known that I, Louis Gurrieri, a subject of the Kingdom of Italy and resident of the city and State of New York, have invented a new, original, and ornamental Design for a Fishing Rod Handle or Analogous Article, of which the following is a specification, reference being had to the accompanying drawing, forming a part thereof.

I claim:

The ornamental design for a fishing rod handle or analogous article, as shown.

LOUIS GURRIERI.
